CLAIM

The ornamental design for a candle including wick, as shown and described.

DESCRIPTION

The patent file contains at least one drawing executed in color. Copies of this patent with color drawings will be provided by the Office upon request and payment of the necessary fee.

FIG. 1 is a perspective view of an embodiment of a candle including wick;
FIG. 2 is a top plan view thereof;
FIG. 3 is a bottom view thereof (the bottom view is the same for all embodiments and thus is not repeated for other embodiments);
FIG. 4 is a front elevational view thereof (the front elevational view is the same for all embodiments and thus is not repeated for other embodiments);
FIG. 5 is a perspective view of the wick shown separately for clarity of illustration;
FIG. 6 is a front elevational view thereof;
FIG. 7 is a top plan view with the bottom view being the same;
FIG. 8 is a perspective view of an embodiment of a candle including wick;
FIG. 9 is a top plan view thereof;
FIG. 10 is a perspective view of the wick shown separately for clarity of illustration;
FIG. 11 is a front elevational view thereof;
FIG. 12 is a top plan view with the bottom view being the same;
FIG. 13 is a perspective view of an embodiment of a candle including wick;
FIG. 14 is a top plan view thereof;
FIG. 15 is a perspective view of the wick shown separately for clarity of illustration;
FIG. 16 is a front elevational view thereof;
FIG. 17 is a top plan view with the bottom view being the same;
FIG. 18 is a perspective view of an embodiment of a candle including wick;
FIG. 19 is a top plan view thereof;
FIG. 20 is a perspective view of the wick shown separately for clarity of illustration;
FIG. 21 is a front elevational view thereof;
FIG. 22 is a top plan view with the bottom view being the same;
FIG. 23 is a perspective view of an embodiment of a candle including wick;
FIG. 24 is a top plan view thereof;
FIG. 25 is a perspective view of the wick shown separately for clarity of illustration;
FIG. 26 is a front elevational view thereof;
FIG. 27 is a top plan view with the bottom view being the same;
FIG. 28 is a perspective view of an embodiment of a candle including wick;
FIG. 29 is a top plan view thereof;
FIG. 30 is a perspective view of the wick shown separately for clarity of illustration;
FIG. 31 is a front elevational view thereof;
FIG. 32 is a top plan view with the bottom view being the same;

FIG. 33 is a perspective view of an embodiment of a candle including wick;
FIG. 34 is a top plan view thereof;
FIG. 35 is a perspective view of the wick shown separately for clarity of illustration;
FIG. 36 is a front elevational view thereof;
FIG. 37 is a top plan view with the bottom view being the same;
FIG. 38 is a perspective view of an embodiment of a candle including wick;
FIG. 39 is a top plan view thereof;
FIG. 40 is a perspective view of the wick shown separately for clarity of illustration;
FIG. 41 is a front elevational view thereof;
FIG. 42 is a top plan view with the bottom view being the same;
FIG. 43 is a perspective view of an embodiment of a candle including wick;
FIG. 44 is a top plan view thereof;
FIG. 45 is a perspective view of the wick shown separately for clarity of illustration;
FIG. 46 is a front elevational view thereof;
FIG. 47 is a top plan view with the bottom view being the same;
FIG. 48 is a perspective view of an embodiment of a candle including wick;
FIG. 49 is a top plan view thereof;
FIG. 50 is a perspective view of the wick shown separately for clarity of illustration;
FIG. 51 is a front elevational view thereof;
FIG. 52 is a top plan view with the bottom view being the same;
FIG. 53 is a perspective view of an embodiment of a candle including wick;
FIG. 54 is a top plan view thereof;
FIG. 55 is a perspective view of the wick shown separately for clarity of illustration;
FIG. 56 is a front elevational view thereof;
FIG. 57 is a top plan view with the bottom view being the same;
FIG. 58 is a perspective view of an embodiment of a candle including wick;
FIG. 59 is a top plan view thereof;
FIG. 60 is a perspective view of the wick shown separately for clarity of illustration;
FIG. 61 is a front elevational view thereof;
FIG. 62 is a top plan view with the bottom view being the same;
FIG. 63 is a perspective view of an embodiment of a candle including wick;
FIG. 64 is a top plan view thereof;
FIG. 65 is a perspective view of the wick shown separately for clarity of illustration;
FIG. 66 is a front elevational view thereof;
FIG. 67 is a top plan view with the bottom view being the same;
FIG. 68 is a perspective view of an embodiment of a candle including wick;
FIG. 69 is a top plan view thereof;
FIG. 70 is a perspective view of the wick shown separately for clarity of illustration;
FIG. 71 is a front elevational view thereof;
FIG. 72 is a top plan view with the bottom view being the same;

FIG. 153 is a perspective view of an embodiment of a candle including wick;

FIG. 154 is a top plan view thereof;

FIG. 155 is a perspective view of the wick shown separately for clarity of illustration;

FIG. 156 is a front elevational view thereof;

FIG. 157 is a top plan view with the bottom view being the same;

FIG. 158 is a perspective view of an embodiment of a candle including wick;

FIG. 159 is a top plan view thereof;

FIG. 160 is a perspective view of the wick shown separately for clarity of illustration;

FIG. 161 is a front elevational view thereof; and,

FIG. 162 is a top plan view with the bottom view being the same.
